UNITED STATES PATENT OFFICE

CARL KÜHNEL, OF BERLIN-CHARLOTTENBURG, GERMANY, ASSIGNOR TO SIEMENS-SCHUCKERTWERKE AKTIENGESELLSCHAFT, OF BERLIN-SIEMENSSTADT, GERMANY, A CORPORATION OF GERMANY

BRUSH FOR THE SUPPLY OF ELECTRIC CURRENT

Application filed November 23, 1928, Serial No. 321,396, and in Germany November 25, 1927.

My invention relates to brushes for the supply of electric current, more particularly to commutators of electrical machines.

In universal and commutator motors, particularly those of small sizes, the disadvantage exists that the commutator brushes serving as current supply members become worn in course of time and are not exchanged in good time owing to insufficient attention.

10 The result is, that the worn brush takes up an oblique position in the holder or that it is even completely worn out and that ultimately the spring or wire helix pressing on the brush slides itself upon the commutator and damages it badly. It may even happen that the local temperature rises become so high, that after a time the commutator fuses or the armature is burned out. This drawback is particularly noticeable in motors for domestic 15 machines, such as vacuum cleaners, floor polishers, pans, kitchen machines, washing machines or the like, since these machines are handled by unskilled operators, who only notice the wear of the brushes after the motor has suffered damage. The object of my 20 invention is to eliminate this drawback.

According to my invention the current supply brushes for the commutators of electrical machines are so designed, that when the 25 brushes have worn to a certain extent vapors, easily noticeable by the eye and the nose are developed, which call the attention of the operator to the fact, that it is time to exchange the brushes. The action of these vapors may 30 be so powerful that the attendant cannot possibly overlook the fact that it is necessary to exchange the brushes.

To attain this result the medium developing the vapors may, for instance, be placed 35 into a cavity at the extremity of the brush. This terminal portion of the brush may, however, equally well be impregnated or saturated with a medium or substance, which develops the vapors when the brush is worn down to that portion. As vapor developing 40 medium a mixture of artificial musk and a priming substance consisting of sulphide of antimony, red phosphorus and potassium nitrate has proved suitable. This medium has 45 the advantage, that it spreads a powerful al-

though agreeable smell without doing injury to the commutator or other parts of the machine. A mixture composed of this priming substance and powdered vulcanite likewise shows a good action. It will be understood, however, that other suitable agents may be employed which develop vapors easily noticeable by the nose or the eye, but harmless to the machine.

An embodiment of my invention is illustrated in the drawing affixed hereto and forming part of my specification.

Referring to this drawing showing a sectional elevation of the brush and holder, 1 is a carbon brush serving for the supply of the current and which is forced against the commutator 3 by a helical spring 2, which also leads the current to the brush. The brush 1 is guided in a holder 4. Near its end it is provided with a lateral bore 5 into which the reacting chemical 6 developing the vapors is inserted after which the bore is closed again. When the wear of the carbon has proceeded up to this point the chemical 6 contained in the bore is evaporated or vaporized by the heat developed by the friction and the current between the commutator 3 and the carbon brush 1.

The current of air sweeping past the motor conveys the vapors thus generated into the room and gives warning of the wear of the brushes by the odor of the vapor developed. In this way due notice is given at the correct time for renewing the brushes.

Various modifications and changes may be 85 made without departing from the spirit and the scope of the invention.

I claim as my invention:

1. A current supply brush, more particularly for the commutators of electrical machines, consisting of a brush member including a portion developing easily noticeable vapors when contacting with the commutator in operation, when the brush has worn to that portion.

2. A current supply brush, more particularly for the commutators of electrical machines, consisting of a brush member having a portion intermediate its ends, impregnated with a vapor developing medium adapted to 100

give a warning by the vapor developed during the commutator operation when the impregnated portion contacts with the commutator.

5 3. A current supply brush, more particularly for the commutators of electrical machines, consisting of a brush member having a cavity intermediate its ends in which is located a vapor developing chemical adapted 10 when contacting with the operating commutator to develop a vapor to give a warning when the brush should be exchanged.

15 4. A current supply brush, more particularly for the commutators of electrical machines, consisting of a brush member having a portion intermediate its ends, filled with a mixture of powdered vulcanite and a priming material consisting of sulphide of antimony, red phosphorus and potassium nitrate, adapted when contacting with the operating commutator to give a warning when the brush should be exchanged.

20 In testimony whereof I affix my signature.

CARL KÜHNEL.
